UNITED STATES PATENT OFFICE.

ALEXANDER E. CAMERON, OF PROVIDENCE, RHODE ISLAND, AND ROBERT S. RILEY, OF WORCESTER, MASSACHUSETTS, ASSIGNEES TO SANFORD RILEY STOKER CO., LTD., OF WORCESTER, MASSACHUSETTS, A CORPORATION OF MASSACHUSETTS.

PNEUMATIC REGULATOR FOR ENGINE-GOVERNORS.

1,817,955.

Specification of Letters Patent.

Patented Oct. 7, 1919.

Application filed September 3, 1915. Serial No. 48,874.

To all whom it may concern:

Be it known that we, ALEXANDER E. CAMERON and ROBERT SANFORD RILEY, citizens of the United States, residing at Providence, 5 county of Providence, State of Rhode Island, and Worcester, county of Worcester, State of Massachusetts, respectively, have invented a new and useful Pneumatic Regulator for Engine-Governors, of which the 10 following is a specification.

The principal object of this invention is to provide a simple and convenient means for controlling the speed of an engine driving a mechanical stoker so as to proportion 15 the speed of the coal feed to the pressure of the air independently supplied to the stoker, and especially to provide an improved mechanism by which pressure of the air is caused to actuate a ball ranger or 20 other means for varying the speed of the engine without affecting the control thereof by the governing balls.

Another object of the invention is to provide means by which the control of the 25 speed will respond comparatively slowly to changes in air pressure so that the speed of the engine will not be changed materially if there is a sudden increase or decrease in the air pressure and the normal pressure is immediately restored. This also has the effect 30 of preventing excessive speeds when the air pressure goes up momentarily.

Reference is to be had to the accompanying drawings, in which—

35 Figure 1 is a side view of a controlling device according to this invention and a ball ranger, including the connections between them; and

Fig. 2 is an end elevation.

40 The controlling device is shown in the form of a stationary closed bottom and open top receptacle 10 provided with a pipe 11 extending into the bottom thereof and up into the interior for compressed air. This 45 pipe is connected with a blower supplying the stoker with compressed air so that the degree of pressure at the stoker will be the same as that in the pipe, and consequently this can be used for the governor control.

50 For this purpose there is within the receptacle 10 an inner receptacle 12 which is movable up and down and has an open bottom and closed top. It will be understood, of

course, that the upper end of the pipe 11 extends up into the air space within the receptacle 12 above the liquid seal and consequently the height of this receptacle 12 will vary according to the pressure of air within. This pipe 11 is connected to individual stoker wind boxes in case of individual control for each stoker, or to a main air duct in case several stokers are driven from the same engine.

Between the two receptacles is a liquid seal, as indicated, which is preferably formed of 55 a kind of thick oil which will not evaporate rapidly. This thick oil, on account of its viscosity, has the advantage of responding slowly to changes in air pressure. Therefore, it is an important feature because it 60 prevents excessive speeds being suddenly produced.

For the purpose of connecting this controller with the engine, we provide a rock shaft 13 having three arms 14, 15 and 16. 65 The arm 14 is pivotally connected directly with the top of the inner receptacle 12. The arm 15 is located at an inclination when the arm 14 is in horizontal position, and on its end is hung a weight 17. On account of the 70 inclination of this arm, the horizontal distance from the center of the weight 17 to the center of the rock shaft 13 increases as the arm 14 rises from a normal horizontal position. That is, the moment caused by the 75 weight will be increased as the inner cylinder rises. When the air pressure within increases, the inner cylinder rises until this moment is sufficient to balance and stop the rise of the inner receptacle. The normal 80 angle of the arm 15 to the horizontal and the amount of weight attached to it preferably 85 are determined by experiment. Therefore, these parts can be so arranged as to provide that a maximum height of the receptacle 12 90 corresponds to a fixed maximum air pressure. As this maximum pressure is relatively small, the depth of the liquid seal can be sufficient always to maintain it within the inner cylinder.

100 The third arm 16 which normally is substantially vertical is connected by a substantially horizontal rod 20 with an arm 21 to which is fixed a pinion or segment 22. This segment meshes with a rack 23 which 105 constitutes a part of a ball ranger for the

engine governor. The ball ranger, as is well known in this art, is a means for varying the length of the connection between the governor balls and the valve to control the 5 position of the valve. This rack is fixed to the valve rod 24, the raising of which tends to open the valve wider to increase the admission of steam to the engine. The bell crank formed by the arm 21 and pinion 22 10 is supported by a pivot or fulcrum 28 on a floating fulcrum carrying member 25 which normally rises and falls on a collar 26 on which it rests and which is not fixed to the rod 24 except through the fulcrum carrying 15 member 25. The governor balls 27 are connected with the collar 26 as usual so that when they rise they allow the collar and therefore the fulcrum carrying member to descend and thus tend to close the admission 20 valve. As the arm 21 does not swing unless the air pressure changes, the governor balls have the usual full control over the engine throttle. We do not claim the construction 25 of this ball ranger, as its details do not constitute a part of this invention, and we are aware of the fact that any other means for regulating the opening of the admission valve could be connected with our controlling device within the scope of this invention 30 as expressed in the claims.

The operation of the device is thought to be obvious. When, on account of low steam pressure, the air pressure supply of the stoker increases, it tends to raise the cylinder 12, which also raises the weight 17 until such time as its moment about the shaft 13 35 is sufficient to balance the increased buoyancy of the cylinder 12. This moves the arm 16 to the right and the arm 21 goes with it, thus raising the rack 23 and the rod 24. The effect of this is simply to take a certain amount of weight off the governor ball arms, but it will be understood that these balls are free to act to rise and fall 40 and that they continue to do so and thus tend to keep the speed constant at the new rate provided by the adjustment described. In this way the speed of the engine varies directly with the air pressure, irrespective 45 of the load on the engine. This is to be distinguished from any arrangement in which the throttle valve might be operated directly by the air pressure because in that case only the amount of steam going to the 50 engine would be controlled and that would not necessarily control the speed because of the variable resistance encountered by the engine when driving an automatic stoker. It will be seen, therefore, that the ball 55 ranger bell crank really controls the speed at which the engine is allowed to be run because it determines the position of the governor valve relative to that of the governor balls and replaces any ordinary speed 60 adjustment of the governor. That is, it 65

serves as a governor adjusting device. Moreover, the governor balls are still there to change the governor valve according to various speeds which may be determined by the various positions of the ball ranger bell 70 crank. In this way the speed of the coal feed is proportioned directly to the pressure of air supplied to the stokers. Nevertheless, the device responds comparatively slowly to the changes in air pressure, and 75 consequently excessive speeds are not attained when the air pressure rises momentarily.

Although we have illustrated and described only a single embodiment of the invention and shown it as connected with a particular type of governor and governor adjusting device, we are aware of the fact that modifications in the construction and arrangement of the controlling device can be 80 made by any person skilled in the art and that it can be applied to other types of governors and governor adjusters, and that it can be applied directly to a rheostat for governing the speed of a motor without departing 85 from the scope of this invention as expressed in the claims. Therefore, we do not wish to be limited in these respects, but what we do claim is:—

1. The combination of the ball ranger of 95 an engine governor, with an open topped receptacle, an open bottom receptacle therein, said receptacles having a liquid seal between them, means for introducing air under pressure into the space within the inner receptacle above the liquid seal, and means connected with and operated by said receptacles, in proportion to the degree of pressure of the air within, for operating said ball ranger to increase the speed at 100 which the engine is to be allowed to run by the ball ranger and governor, as the air pressure rises, irrespective of the load on the engine, and leaving the governor free thereafter to maintain the speed constant. 105

2. In a device for regulating the speed of an engine for driving a mechanical stoker, the combination with the valve rod of the engine and a governor for operating said rod, of means connected with the air supply 110 to the stoker for adjusting the governor for increasing the speed of the engine upon an increase in the pressure of the air in said supply, said means comprising retarding means so as to act on the governor only after 115 the pressure has risen materially, said governor being connected with the rod so as to retain its control over the engine both before and after adjustment, whereby it will tend to keep the speed constant at the new 120 speed.

3. In a device for regulating the speed of an engine for driving a mechanical stoker in proportion to the pressure of the air supplied to the stoker, the combination of a sta- 125 130

tionary receptacle and a movable receptacle telescoping together, means for introducing air pressure from the stoker into the space between said receptacles, a liquid seal between said receptacles, a rock shaft, a normally horizontal arm connected with the movable receptacle and fixed to the rock shaft, a normally inclined arm fixed to the rock shaft and having a weight thereon whereby as the movable receptacle rises, the second arm will move toward horizontal position and the effect of its weight will be increased, a third arm on the rock shaft, and a governor adjusting device connected with said third arm and operated thereby.

4. In a device for regulating the speed of an engine for driving a mechanical stoker in proportion to the pressure of the air supplied to the stoker, the combination of two telescoping receptacles having a liquid seal, means for introducing air pressure from the

stoker supply to control the relative positions of said receptacles, means for resisting the elevation of the movable one of said receptacles, mechanical connections between 25 said means and movable receptacles arranged so that as it rises it will become harder to raise it, and a governor adjusting device connected with the movable receptacle and operated thereby.

In testimony whereof we hereunto set our hands, in the presence of the subscribing witnesses.
